UNITED STATES PATENT OFFICE.

STANLEY MCCLATCHIE, OF CAMBRIDGE, MASSACHUSETTS, ASSIGNOR TO BENJAMIN ELECTRIC MANUFACTURING COMPANY, OF CHICAGO, ILLINOIS, A CORPORATION OF ILLINOIS.

ELECTRICAL CONNECTER DEVICE.

Application filed January 16, 1920. Serial No. 351,820.

To all whom it may concern:

Be it known that I, STANLEY MCCLATCHIE, a citizen of the United States, residing at Cambridge, in the county of Middlesex and 5 State of Massachusetts, have invented new and useful Improvements in Electrical Connector Devices, of which the following is a full, clear, concise, and exact description, reference being had to the accompanying 10 drawing, forming a part of this specification.

My invention relates to electrical connector devices. More specifically, it relates to swivel attachment plugs.

Among the objects of my invention are 15 to provide an improved swivel attachment plug which can be easily wired, and in which the wiring connections are well made, which can be conveniently handled, and which will be simple in construction, easy to manufacture and durable and efficient in use.

Another object of my invention is to improve certain features of construction of electrical connectors.

Further objects will appear from the 20 detailed description to follow and from the appended claims.

In the drawings in which an embodiment of my invention is shown by way of illustration:

30 Fig. 1 is a side elevation of an attachment plug;

Fig. 2 is an axial section of the plug shown in Fig. 1;

Fig. 3 is an axial section of the plug 35 on the line 3—3 of Fig. 2;

Fig. 4 is a side elevation of the binding terminal carrying portion of the plug;

Fig. 5 is a plan view of the plug with the cap removed;

40 Fig. 6 is a sectional view showing the manner in which the binding terminal carrying portion is removed from the threaded shell, and

Fig. 7 is a bottom view of the binding 45 terminal carrying portion.

In order to give a general idea of the construction shown, it is here stated that the connector device illustrated comprises a two-part insulating base 10, which supports 50 the center contact 11, and a pair of wiring terminals, and a threaded shell contact 12, having an inwardly extending flange portion 13, which is held in place by and between the two parts of the insulating base

10. The two-part insulating base 10 comprises a body portion 14, located substantially inside the threaded shell contact 12, which supports the wiring terminal 15 for the center contact, and a cap portion 16 located outside of the threaded shell contact, 60 for supporting the center contact 11.

The construction is such that when the cap 16 is disconnected from the body portion 14, the body portion can be removed from the threaded shell contact 12 by working it past the inwardly extending flange portion 13 of the threaded shell contact, and such that in wiring the plug the threaded shell contact 12 with the thumb piece 17 can be slipped on over the feed wires, the 70 ends of these wires brought into their proper position with respect to the wiring terminal parts carried by the body portion 14, and this body portion 14 then worked into place within the threaded shell contact past the 75 flange portion 13 of this threaded shell contact. This working of the body portion 14 past the flange portion 13 is shown in Fig. 6, and is accomplished by a relative tilting movement between the body portion and the 80 threaded shell contact, which will be described in detail later.

After the body portion 14 has slipped into place past the flange 13, the cap portion 16 is put in place, and secured to the body portion 14, this connection between the parts 14 and 16 serving to hold the parts together in their proper position with respect to each other and the threaded shell contact 12. As shown in Fig. 3 the binding screw 15 for the center contact 11 is in axial alignment with said center contact, both the center contact 11 and the binding screw 15 being threaded into an eyelet 18, which extends through an opening in the body portion 14. In order to prevent the end of the feed wire 19, which is connected with the binding screw 15, from being jerked out from under the head of this binding screw, and in order to relieve this binding screw from the strain, a strain-relief member 20 is provided, which comprises a metal stamping which is secured to the body portion 14 by means of the eyelet 18, into which the binding screw 15 is threaded. 100 The bared end of the feed wire 19 is secured under the head of the binding screw 15 and is then looped up over this strain-

relief member 20, so that the wire 19 is first led upwardly from underneath the head of the screw 15, brought around over the strain-relief member, and through the 5 opening 21 in the thumb piece. This bending of the feed wire around the strain-relief member prevents any considerable pull being exerted on that part of the wire which is adjacent the binding screw.

10 The thumb piece 17 has an annular inwardly extending insulating barrier portion 22, which cooperates with a barrier portion or projection 23 on the insulating body 14 to keep the stray strands of the wire 19 from getting into engagement with the threaded shell contact 12.

As shown in Figs. 1 and 2, the feed wire 24 for the threaded shell contact is clamped between the insulating body 14 and the cap 16 and thus forced firmly into engagement with the annular sliding contact member 25, which is secured to the cap 16. The sliding contact member 25 thus acts as a terminal for the feed wire 24. This clamping 25 of the feed wire 24 between the two parts of the insulating base is accomplished simply by screwing the center contact 11 into the internally threaded eyelet 18. In order to insulate the bared end of this feed wire 30 25 from the center contact screw 11, the insulating body 14 is provided with an up-standing annular flange or barrier 26, which surrounds the screw 11 when the parts are in assembled position, the bared end of the 35 feed wire 24 being wrapped around this annular barrier as shown in Figs. 4 and 5. To further insure against stray strands of the ends of the wire 27 getting into engagement with the center contact screw 11, the cap 16 may be provided with a downwardly extending annular flange or barrier portion 27, which extends downwardly into the annular space between the center contact screw 11 and the annular barrier 26. The 40 annular barrier 26 fits in a corresponding recess in the cap, this interfitting part serving to center the cap with respect to the body portion 14, to facilitate assembling of the parts, and to enable the center contact 45 screw 11 to be lined up with the bushing 18. The annular barrier 26 also serves as a handle to assist in removing the body 13 with respect to the threaded shell contact 12, as will be shown in Fig. 6.

50 In order to prevent the ends of the feed wire 24 from being jerked out from engagement, and in order to release the strain on this binding terminal construction, the body portion 14 is provided with a tortuous passage 28 (Figs. 6 and 7) in which the feed wire 24 is laid; the stems in this passage serving to relieve the binding terminal from strain.

55 The sliding contact member 25 may be a sheet metal stamping secured in place on

the cap 15 by being flanged over as indicated at 29. The threaded shell contact 12 may be secured to the thumb piece 17 by screwing it thereon, and pressing the shell contact into recesses in the thumb piece 17 70 as indicated at 30. (Figs. 3 and 5.)

Referring again to the tortuous passage 28, I have designed this so that it can be formed by an inwardly extending projection on the die, meeting and passing an inwardly extending projection on the matrix, as the part is being molded.

As shown in Fig. 6, the side wall 31 at the upper portion of the tortuous passage is in alignment with the opposite side wall 32 at the bottom of this tortuous passage. The upper portion of the passage is formed by an inwardly extending projection on a downwardly moving die, the end of which extends as far as the portion 33 of the passage, and the lower portion of the passage 28 is formed by an inwardly extending projection on the matrix, the upper end of which extends up to the portion 34 of the passage, the edge of the inwardly extending projection on the die meeting and passing the upper edge of the inwardly extending projection on the matrix.

I will now describe more in detail the construction whereby the body portion 14 can be slipped into and out of the threaded shell contact 12. As shown in Figs. 2, 4, 6 and 7, this body portion 14 is provided with an elliptical flange portion 35, the smaller diameter of which elliptical flange is less than the diameter of the circular opening in the flange 13 of the threaded shell contact, and the major diameter of which elliptical flange is greater in diameter than the diameter of this circular opening in the flange of the shell. This elliptical flange thus constitutes in effect two laterally extending wing portions, which can be caught under the circular flange 13 by sidewise and tilting movement of the body 14 with respect to the shell contact.

After the body portion 14 has been located in its proper position in the shell contact 12, with both sides of the flange 35 caught under the flange 13, the cap 16 is slipped in place onto the body portion 14, and the center contact screw 11 is screwed into the bushing 18 to draw the two parts of the insulating base substantially together to clamp the feed wire 24 firmly in place, and to hold the parts of the base together. This screwing in of the screw 11 draws the circular shoulder portion 36 of the base 14 up into the circular opening in the flange 13 of the threaded shell contact and thus centers the insulating base with respect to the shell contact.

The method of wiring and the circuit has been indicated in connection with the description of the construction. The plug is

wired by slipping the thumb piece 17 and the insulating shell 12 over the ends of the feed wires 19 and 24. The end of the feed wire 19 is then secured under the head of the 5 binding screw 15, and the wire is looped up over the strain-relief member 20. The wire 24 is then placed in the tortuous groove 28 and the bared end wrapped around the insulating barrier 26. The threaded shell 10 contact 12 is then slipped up on the cord and the insulating body portion 14 is worked past the flange 13 into the interior of the threaded shell contact 12. The cap 16 is then slipped on over the body portion 14 and 15 the center contact screw 11 is inserted in place and screwed into the bushing 18 to draw the two parts of the insulating base firmly together and to clamp the feed wire 24 in place.

20 The circuit is from the center contact 11 through the bushing 18, feed wire 19, through whatever translating device is connected with the plug, to the feed wire 24, and thence through the sliding contact member 25, to the threaded shell contact 12.

This application is a continuation as to common subject matter claimed herein of my copending application Serial No. 284,113, filed March 21, 1919.

30 Having thus described my invention, what I claim as new and desire to secure by Letters Patent of the United States is:

1. A swivel attachment plug comprising a swivel contact, having an inwardly extending annular flange at its entering end, a two-part insulating base, the parts having portions located on opposite sides of the flange respectively, for positioning the contact with respect to the base and binding 35 terminal members and a center contact supported by said base, said center contact construction comprising a screw, the wire for the shell contact being clamped between the parts of the base by the action of said center 40 contact screw.

2. A binding terminal construction comprising a binding screw beneath the head of which the wire is caught, a strain-relief member around which the wire is bent and an eyelet for securing said strain-relief member in position, said binding screw being 50 threaded into said eyelet.

3. A swivel attachment plug comprising an insulating body, and a contact swiveled on said body, said body being divided transversely into forward and rearward parts, means for securing the parts together with an annular space therebetween, said contact having a flange extending into said annular space to restrain axial movement of the contact relative to the body, the rearward part of the body having a diameter sufficiently small to permit it to be inserted into said contact through the forward open end thereof, and having an eccentric portion for extending behind said flange when the rearward part has entered the contact.

4. A swivel attachment plug comprising an insulating body and a contact swiveled on said body, said body being divided transversely into forward and rearward parts, means for securing the parts together with an annular space therebetween, said contact having a flange extending into said annular space to restrain axial movement of the shell 70 relative to the body, the rearward part of the body having a diameter sufficiently small to permit it to be inserted into the contact through the forward opening thereof and having an eccentric portion extending behind said flange when the rearward part is centered in the contact, one of said body parts having a projection to fit into said flange to center both parts of said body, the parts being connected together by said 75 means.

In witness whereof, I have hereunto subscribed my name.

STANLEY McCLATCHIE.
